UNITED STATES PATENT OFFICE

WILLIAM A. FROTHINGHAM AND THOMAS W. FROTHINGHAM, OF PORTLAND, MAINE

LAUNDRY-SORTING APPARATUS

Application filed May 2, 1929. Serial No. 359,858.

This invention involves a method of and apparatus for re-assembling into their original groups or lots units which have been indiscriminately commingled for the performance of some particular operation or operations upon them and later must be re-collected into their original groups. For the purposes of this application we shall discuss our invention in its adaptation to the assorting or re-grouping of articles of laundry in which use it finds a field of immediate utility. It is to be understood however that this treatment is purely illustrative and in no way limiting and that the method and apparatus constituting our invention may be adapted to various arts without departing from fundamental principles.

Under one system of modern laundry operation, it is customary as each bundle or lot of soiled laundry is opened, checked and listed to pin or otherwise attach to all of the articles comprised in such lot tags or markers all bearing the same identifying number. These tags or markers remain affixed to the articles in that particular lot during the subsequent operations of washing, rinsing, etc. and enable the assorter finally to re-assemble all the articles comprised in that lot for return to the owner.

One characteristic objection to such method however has been that the assorter has no means of knowing how many articles were comprised in any particular lot and consequently cannot be certain until all of the articles in all of the lots have been checked whether or not all articles of a particular lot have been accounted for.

To the end therefore of overcoming this objection, we have devised our present invention. According to it, we provide means which are so associated with the operation of assorting as visually to indicate at all times to the assorter the total number of articles in any lot so that she may know instantly and at a glance how many articles of any

particular lot are outstanding. The use of these totalizing indicators is so related to the use of the numbered markers or tags for the individual articles and with the numbered collection arms of the assorting or re-grouping drum as to enable the assorter by simply counting the articles in any particular lot which have actually been re-grouped and comparing with the indicated total for such group to know instantly the number of articles outstanding in that particular lot or group. This makes for an accuracy of check never heretofore attained and avoids shortages and improper mixing of articles of different lots, since the operative will know at once whether she has too few or too many articles on any particular lot-number suspension arm of the assorting drum.

In conjunction with the use of such totalizing indicators, we provide an assorting or re-grouping drum which is especially designed for the successful practice of our method and which constitutes at once an efficient and convenient apparatus for the assorting and re-grouping of the articles according to their lot numbers.

As illustrative of our invention we show in the accompanying drawings apparatus for the practice thereof which we have found highly satisfactory in use and well adapted for the purposes intended.

In the drawings:—

Figs. 1 and 2 are respectively a top plan and a central vertical section through an assorting or re-grouping drum in accordance with our invention.

Fig. 3 is a fragmentary elevation of the assorting head, particularly illustrating the manner of use of our totalizing indicators.

Fig. 4 is a detail view of the storage box or receptacle for the totalizing indicators.

Fig. 4^a is a detail view of an indicator.

Fig. 5 is a perspective view of a numbered pin box, and

Fig. 5^a is a similar view of a numbered marking pin.

Our assorting drum comprises a relatively stationary base A on which is journaled an upright shaft B carrying a revoluble head C. Surmounting the base and revolving with the head is an annular catch pan D. The head and pan are connected by a spaced series of substantially vertical tie rods E including an intermediate ring F having projecting handles G by means of which the head and pan may be revolved as a unit relative to the base.

The head is stepped to provide a series of concentric banks or shelf areas. As here shown, two banks H and J are provided. The rim of the head has extending radially therefrom an annular series of spaced suspension arms K, which may be pivoted thereto as indicated at L, and which are consecutively numbered as shown in Fig. 3.

Each arm number corresponds with a lot number, that is to say, when a particular bundle of clothes is opened, it is assigned a lot number and each article comprised in such lot has affixed thereto a numbered tag or pin M bearing such lot number, so that all of the articles in a particular lot bear the same number. These tags or pins are detailed in Fig. 5^a and are kept in slotted-bottom boxes or receptacles N, one of which is detailed in Fig. 5. The pin boxes N are consecutively numbered to correspond with the numbering of the arms K, and in the practice of our method are subsequently placed upon one or the other of the banks or shelf areas H or J of the revoluble head immediately behind the correspondingly numbered suspension arm K. By forming the shelf areas as concentric banks, we are enabled to stagger the pin boxes N relative to each other so that each box lies immediately behind its correspondingly numbered arm K.

After a bundle or lot has been assigned a lot number and the individual articles in such lot have been tagged with the pin markers M bearing that number, a totalizing indicator P (Fig. 4^a) is placed in that particular pin box N whereby visually to indicate to the assorter the total number of articles comprised in that lot. The pin box, with the indicator P exposed to view therein, is then placed on one of the shelf areas or banks H or J immediately behind its correspondingly numbered arm K. These indicators P are stored in a slotted bottom box or receptacle Q (Fig. 4) generally similar to the pin boxes and the construction of such indicators is such as to enable them conveniently to be inserted into and removed from either box as occasion requires. To this end, each indicator comprises a relatively narrow stem portion P' adapted to fit within the vertical slots of the boxes and a relatively broad flag or signal

portion P² adapted to bear a total-indicating number.

The lots are, of course, indiscriminately commingled during the several laundering operations, as washing, rinsing, etc., but are assorted or re-assembled according to their particular lot number, all of the articles in any particular lot number being assembled on its correspondingly numbered arm K. In this operation, the totalizing indicators P placed in the pin boxes immediately behind such correspondingly numbered arms are of the greatest convenience and assistance to the assorter, making for an accuracy of checking not heretofore possible in the art. The assorter simply notes in each lot the total number of articles to be accounted for in such lot as shown to her by the indicator behind the correspondingly numbered suspension arm K. If there are actually eight pieces in lot 50 for example, she instantly verifies this by a glance at the indicator P in the pin box behind the arm numbered 50 on which arm she will hang all articles bearing a number 50 pin tag, and when all eight articles are present on that arm she knows without further check-up that the count for that particular lot is complete. Thus shortages are instantly detected, as are over-counts, as where a garment has been inadvertently hung upon the wrong arm.

The construction of the drum itself is such as most conveniently to be adaptable to such use, since the pin boxes with their totalizing indicators, may all be displayed in plain sight immediately behind their correspondingly numbered arms K, the apparatus may be rotated as a unit to bring any desired group of numbered arms K into position relative to the assorter, and the trough or pan D will prevent the suspended articles on the arms from sweeping or touching the floor.

Various modifications in method and apparatus may obviously be resorted to within the spirit and scope of our invention as defined by the appended claims.

What we therefore claim and desire to secure by Letters Patent is:

1. In a laundry sorting apparatus, a rotatable member comprising a stepped head adapted to support numbered pin trays, and hanger arms extending radially from said head and numbered to correspond with the numbering of said pin trays.
2. In a laundry sorting apparatus, a rotatable member comprising a stepped head adapted to support numbered pin trays, radial hanger arms disposed thereon, and an annular bottom trough disposed beneath said arms.
3. In a laundry sorting apparatus, a rotatable member comprising a stepped head presenting concentric banks adapted to support numbered pin trays, radial hanger arms disposed thereon, said arms being numbered to

correspond with the numbering of said pin trays and the stepped formation of the head permitting each pin tray to be disposed immediately behind its correspondingly numbered arm.

5 4. In a laundry sorting apparatus, a rotatable member comprising a stepped head presenting concentric banks adapted to support numbered pin trays, radial hanger arms disposed thereon, and an annular bottom trough disposed beneath said arms, said arms being numbered to correspond with the numbering of said pin trays and the stepped formation of the head permitting each pin tray to be disposed immediately behind its correspondingly numbered arm.

10 5. In a laundry sorting apparatus, a rotatable stepped head adapted to support numbered pin trays, hanger arms extending radially from said head and numbered to correspond with the numbering of said pin trays, and indicators disposable in each pin tray and indicative of the outstanding total of articles identified by the pins of each particular pin tray.

25 6. In a laundry sorting apparatus, a stepped rotatable head presenting concentric banks adapted to support numbered pin trays, radial hanger arms extending from said head and numbered to correspond with the numbering of said pin trays, the stepped formation of the head permitting each pin tray to be disposed immediately behind its correspondingly numbered arm, and indicators disposable in each pin tray and indicative of the outstanding total of articles identified by the pins of each particular pin tray.

30 7. In a laundry sorting apparatus, a rotatable member comprising a stepped head presenting relatively flat inner and outer concentric areas disposed in different vertical planes and each of a width sufficient to receive and support a plurality of numbered pin trays, and hanger arms extending radially from the rim of the lower of said areas and numbered to correspond with the numbering of said pin trays.

45 8. In a laundry sorting apparatus, a stepped head presenting a plurality of shelf areas disposed in different vertical planes, a radial series of hanger arms projecting from said head, and an annular bottom trough rotatable with said head and disposed beneath said arms at a distance to receive the lower ends of articles suspended from said hanger arms to prevent them from touching the floor.

50 9. In a laundry sorting apparatus, a vertical support, a stepped head at the upper end of said support presenting a plurality of shelf areas disposed in different vertical planes, a plurality of hanger arms extending radially from said head, an annular bottom trough adjacent the lower end of said support, a spaced series of tie rods extending from said head to said trough and including an intermediate

ring, and operating handles projecting from said ring for enabling the head and trough to be revolved as a unit.

10 10. In laundry sorting apparatus, a stepped head presenting inner and outer concentric shelf areas disposed in different vertical planes, said areas being of a width to receive and support a plurality of numbered pin trays, and numbered hanger arms projecting from the rim of said outer shelf area.

15 In testimony whereof we affix our signatures.
